ABSTRACT: A mechanism for operating a door including a reversible electric motor, a rotatable shaft connected therewith, with the shaft having a given rotational speed, a worm having a bore extending the entire length thereof, with the shaft being slidably received therein, key means provided in said bore for locking the shaft into rotational engagement with the worm, a worm gear in working engagement with the worm, a worm gear in working engagement with the worm and having a given rotational speed proportioned to the rotational speed of the shaft, door closure actuating means operatively connected with the worm gear, limit switch means electrically connected to the motor and disposed in a region adjacent the worm, and switch actuating means mounted on the worm and contacting the limit switch means when the rotational speed of the worm gear varies from the given rotational speed of the worm.

PATENTED JAN 11 1972

FIG. 1

FIG. 2

INVENTOR.

LUCIEN LAFONTAINE

FIG. 3

1
GARAGE DOOR OPENER

This invention relates to a mechanical way to actuate a limit switch or switches for stopping an electric motor or reversing its polarity in "garage door operators" and to the use of a drum instead of a pulley to avoid slippage of the wire cable when used instead of a roller chain.

Further details of the invention will become apparent from the accompanying single sheet of drawing and from the following description and claims.

FIG. 1 represents an ordinary garage door operator.

FIG. 2 represents the disposition of the worm on the shaft of the motor with arrangement of the springs, the spacers with limit fingers and the bearings.

FIG. 3 represents the worm driving the worm gear which in turn drives the drum.

On the shaft of the electric motor (FIG. 2) there are a worm A, two springs B, two bushings or bearings C, two spacers with limit fingers D, or a worm, one spring, one bushing or bearing, one spacer with limit finger(s).

The worm follows the rotation of the motor by the use of a key (FIG. 3) inserted in the keyway of the shaft and the worm, or by a flat on the shaft of the motor and a corresponding flat in the hole of the worm.

When the motor starts turning in one direction the worm drives the worm gear (FIG. 2) F which in turn drives a chain sprocket or a pulley or a drum (FIG. 1 & 3) E.

The chain sprocket or the pulley or the drum drives a roller chain or a wire cable attached to both ends of the carriage that slides on the U channel or T bar, the said carriage being attached indirectly to the door by an arm (FIG. 1).

When the door is fully opened or fully closed or if the door, in its way down or up, encounters an obstacle or if the door does not operate properly, the speed of the worm gear reduces or the worm gear stops completely.

As the motor continues turning at its normal speed the worm will then slide on the shaft of the motor pushing the limit finger(s) (FIG. 2D) that actuates the fixed or adjustable limit switch(es) (FIG. 2G) that stops the motor or reverses the rotations of the motor if the limit switch is connected to a relay (reversing contactor) that reverses the polarity of the motor.

Therefore the mechanical way as claimed and described above to actuate a limit switch(es) to stop the motor or reverse its polarity resides essentially in the fact that the worm instead of being firmly secured on the shaft of the motor slides back and forth on the said shaft and is kept in normal position by the spring(s) that will deflect under pressure of the worm allowing the limit finger(s) on the spacer(s) to actuate a limit switch(es) that stop the motor or reverse its polarity through a reversing contactor. The bushing(s) or bearing(s) (FIG. 2C) are used to avoid friction between the worm and the

spacer(s).

A further object of the invention is to avoid the slippage of a wire cable, when used instead of a roller chain, by using a drum instead of a pulley, on which drum the wire cable is enrolled or firmly secured, and on which drum one length of the wire cable attached to one end of the carriage of the operator rolls itself while the other length of the wire cable attached to the other end of the carriage unrolls itself at the same time (FIG. 1-2-3-E).

10 Although a specific embodiment of the invention has just been described it will be understood that various modifications may be made thereto without departing from the invention the scope of which is only to be construed from the appended claims.

15 I claim:

1. A mechanism for operating a door comprising, in combination, a reversible electric motor; a rotatable shaft connected therewith and being driven thereby, said shaft having a given rotational speed; a worm having a bore extending the 20 entire length thereof, said shaft being slidably received in said bore; key means provided in said bore locking said shaft into rotational engagement with said worm but allowing longitudinal movement of said worm on said shaft; a worm gear in working engagement with said worm, said worm gear having a given rotational speed proportioned to the rotational speed of said shaft, door closure actuating means operatively connected to said worm gear; a pair of limit switch means electrically connected to said motor and each oppositely disposed in a region adjacent to the extremities of said worm, said pair of 30 limit switch means including a first limit switch for stopping said motor from rotating said shaft and a second limit switch for causing said motor to reverse the rotation of said shaft; a pair of switch actuating means each mounted at one extremity of said worm and including a first finger for contacting said 35 first limit switch and a second finger for contacting said second limit switch; and a pair of spring means axially mounted on said motor shaft and disposed thereon on each side of said switch actuating means maintaining said worm in a normal position in relation to said worm gear; said worm being longitudinally slidable on said shaft when the rotational speed of said worm gear varies from the rotational speed of said worm whereby said pair of spring means cause said first finger to contact said first limit switch to stop the rotation of said shaft when the worm slides longitudinally in one direction on said shaft and cause said second finger to contact said second limit switch to reverse the rotation of said shaft when the worm slides longitudinally in the other direction on said shaft.

40 45 50 2. A mechanism as defined in claim 1 wherein said door closure actuating means include a drum and a wire cable enrolled on said drum.
